UNITED STATES PATENT OFFICE.

JAMES BROPSON, OF CLEVELAND, OHIO.

CLOSET-SEAT BUMPER.

No. 926,466.

Specification of Letters Patent.

Patented June 29, 1909.

Application filed June 1, 1908. Serial No. 435,875.

To all whom it may concern:

Be it known that I, JAMES BROPSON, a citizen of the United States, and resident of Cleveland, in the county of Cuyahoga and State of Ohio, have invented certain new and useful Improvements in Closet-Seat Bumpers, of which I hereby declare the following to be a full, clear, and exact description, such as will enable others skilled in the art to 10 which it appertains to make and use the same.

The objects of the invention are to provide elastic bumpers for a closet seat, and the particular improvements designed in this 15 specific form of invention over the past art are to provide a more efficient, convenient and practical means for securing the bumpers and at the same time a securing means which will not interfere with their removal 20 when they have become worn or have lost their elasticity.

The invention in detail comprises means for securing the bumpers to the upper edge of the closet bowl and also has reference to a 25 metallic engaging surface for the bumpers.

The invention is illustrated in the accompanying drawings, hereinafter further described and specifically pointed out in the 30 claims.

In the accompanying drawings Figure 1 is a longitudinal section of a "bowl" showing the manner of arranging the bumpers in the rim therefor; Fig. 2 is a vertical section through a portion of the rim showing a 35 bumper of elastic and vulcanizable material, resting in a socket formed in the rim of the bowl; Fig. 3 is a side elevation of a bumper and Fig. 4 a top view thereof; Fig. 5 is a vertical section of the rim of a bowl showing the 40 bumper inserted therein and a metallic button inserted in the bumper to provide a more durable striking surface therefor.

In the views the bowl B is shown to be provided with a rim 1, 2 is a socket sunk in 45 the aforesaid rim which flares laterally at the base. Upon the base of this socket a pyramidal elevation 3 is shown the apex of which is located underneath the reduced portion P of the socket opening, 4 is the bumper formed 50 of elastic, compressible, vulcanizable ma-

terial such as rubber. This bumper is provided with a protruding head, with a neck 8', and with a flaring base 5. The neck and base are adapted to fit closely within the socket, and the base of the bumper is recessed at 6 so as to make the edges of the base more flexible so that they can be compressed into the narrowed neck of the socket. A further object of the recess is to fit over the elevation 3 in the bottom of the socket, so that the thin edges of the base of the bumper will be forced outward by the sides of the elevation and spread to form a dovetail closely fitting the sides of the dovetail socket. The bowl rim is preferably raised about the neck of the socket opening at 7 to give sufficient thickness of material in which to form the socket. This lip or raised portion 7 about the edge of each socket opening 2 serves also to give protection to the bumper, 70 from water lying on the rim of the bowl, and to keep the bumper dry, since the action of the closet water would rot the bumper, and at the same time gives greater thickness to the material of the bowl.

In Fig. 5 a metallic button 8 is shown having a stem 10 and a reduced head 9 at the lower end which is inserted in an opening 11 of similar shape to the stem and head. This metallic button can be made of aluminum or 80 other substantially non-oxidizing metal if desired and serves to reinforce the bumper and increase its longevity.

The bumpers can be made of any diameter or length without departing from the spirit 85 of the invention and can be used with closets of any material.

Having described the invention what I claim as new and desire to secure by Letters Patent is:—

1. The combination, with the rim of a closet "bowl" provided with a dovetail socket, having a reduced opening and an expanded base, a central elevation on the base of the socket underneath the said reduced opening and a raised margin about the neck of the reduced opening, of a compressible bumper provided with an external head, a reduced neck and expanded base, and having a recess in its base adapted to correspond 95 100

with the said elevation in the base of said socket.

2. The combination with the rim of a closet "bowl" having dovetailed socket therein, and an expanding means upon the base of the socket and a raised rim about said dovetailed socket, of a bumper of compressible and elastic material, adapted for

insertion in said socket, and the base of which engages said expanding means.

In testimony whereof I hereunto set my hand this 20th day of May 1908.

JAMES BROPSON.

In presence of—
FIELDER SANDERS,
Wm. M. MONROE.
